W. W. MITKEWICH

AIR WRITING WITH SEARCHLIGHT BEAMS

Filed May 17, 1926

Attorney

UNITED STATES PATENT OFFICE.

VLADIMIR W. MITKEWICH, OF BROOKLYN, NEW YORK, ASSIGNOR OF THIRTY-THREE AND ONE-THIRD PER CENT TO RICHARD VITOLO AND THIRTY-THREE AND ONE-THIRD PER CENT TO DANIEL ANDRE RODIONOFF, BOTH OF NEW YORK, N. Y.

AIR WRITING WITH SEARCHLIGHT BEAMS.

Application filed May 17, 1926. Serial No. 108,730.

The present invention relates to a highly novel yet simple means for forming words, letters, or characters in the air at night by the employment of light beams.

One of the important objects of the present invention is to provide a means of the above mentioned character wherein a spot light is used in conjunction with reflectors for forming the desired letters, words, or characters in the air at night so that the figure, word, or character thus formed will be visible for a considerable distance and will attract considerable attention, thus possessing the necessary essentials for properly displaying an advertisement.

Another important object of the invention is to provide a means for supporting the reflectors in predetermined positions in the air so that when the light rays or beams from the spot light are drawn onto the reflectors, the same will cooperate with one another to form the predetermined letter or word.

A further object of the invention is to provide a device of the above mentioned character which is simple in construction, inexpensive, strong, and durable and further well adapted to the purpose for which it is designed.

Other objects and advantages of the invention will become apparent during the course of the following description taken in connection with the accompanying drawing.

In the accompanying drawing forming a part of this application and in which like numerals designate like parts throughout the several views:

Figure 1 is a view showing the arrangement of the reflecting mirrors on the supporting wire and also illustrating diagrammatically the manner in which the light rays or beams are intercepted by the mirrors.

Figure 2 is a detail of one of the mirrors showing the light rays being reflected therefrom at right angles to the reception of the rays or beams.

Figure 3 is a top plan view of one of the

reflectors showing the suspension means 50 therefor.

Figure 4 is a view showing the letter "K" formed by the intercepting light rays of three spot lights.

Figure 5 is a view showing the same letter formed by a single spot light and reflecting mirrors arranged in a predetermined manner, and

Figure 6 is a diagrammatic view showing the arrangement of some of the reflecting 60 mirrors.

In the drawing, wherein for the purpose of illustration is shown the preferred embodiment of my invention, with reference more particularly to Figure 4 there is shown 65 the formation of the letter "K" which letter is formed by arranging three spot lights numbered 1, 2 and 3 respectively in such a manner as to cause the light rays or beams therefrom to interfit in the manner as clearly illustrated in said figure. In this manner, any desired letter or character may be formed in the air at night by having the light ray beams pass through the air in different directions and illuminating the 75 particles of dust and moisture in the air.

The invention further comprises the provision of a plurality of reflecting mirrors, the same being adapted to be suspended in the air, and the manner in which each mirror is supported is clearly shown in Figure 3. With reference now particularly to this figure, it will be seen that the mirror 4 is attached at its corners to the intermediate portions of the pair of spaced rods or wires 80 5 and 6 respectively, the ends of which are attached to the parallel spaced elongated rods or wires 7 and 8 respectively. The last mentioned pair of rods or wires 7 and 8 are secured at their respective ends to the ends 90 of suitable cross bars illustrated at 9 and these cross bars are supported transversely of a pair of vertical standards or masts 10 and 11 respectively as is shown more clearly in Figure 1. Each cross bar is secured to 95 the mast or standard by means of a clamp illustrated at 12 in Figure 3.

As many of these pairs of rods or wires

2
7 and 8 may extend between one pair of spaced standards or masts in spaced superposed relation as may be desired as is clearly shown in Figure 1 and for the purpose of 5 arranging the reflecting mirror in horizontally spaced relation, it will be necessary to provide additional pairs of supporting standards or masts and also additional pairs of rods or wires 7 and 8 as is readily obvious from the construction shown in Figures 1 and 6.

A series of reflecting mirrors such as are shown at 4 are adapted to be suspended between the rods 7 and 8 through the medium 15 of the mirror supporting wires 5 and 6 as is necessary to form a predetermined letter, figure, or word, and in certain instances, a reflector such as is shown at 13 is employed for dividing the light rays which are projected onto said reflector. This type of reflector comprises a pair of mirrors arranged 20 in intersecting relation so that certain of the light rays will be directed to the right and left respectively.

25 In the present instance, I have shown the mirrors arranged in such a manner as to form the word "light" although it is to be understood that these mirrors may be arranged in any other manner in order to form 30 any other word which is to be displayed. A relatively large reflecting mirror 14 is supported at an angle between the lower and next adjacent pair of spaced rods or wires 7 and 8 as clearly shown in Figure 1 and 35 furthermore one end of the lowermost pair of supporting rods or wires 7 opposite the reflector 14 is inclined upwardly so as to merge with the adjacent end of the next adjacent pair of rods or wires. A screen or 40 shade such as is shown at 15 is supported on the mast or standard 11 for stopping the light rays which are projected horizontally from the reflecting mirror 14. A relatively large spot light or other source of illumination 45 has its light beams directed vertically against the reflecting mirror 14 and the several smaller mirrors 4 which are supported between the wires or rods 7 and 8 will receive the light rays or beams reflected from the mirror 14, and in turn these mirrors will 50 direct the light rays in the various directions illustrated in the dotted lines in Figure 1 and by employing suitable screens or shades 55 16 at predetermined places on the wire supporting structure, the light rays or beams will be cut off so that the word "light" will be formed by the light rays or beams in the air by reason of the light rays illuminating the particles of dust and moisture in the atmosphere.

In Figure 5 of the drawing there is illustrated the manner in which the letter "K" is formed wherein a single spot light 17 and a series of reflecting mirrors 18 and the

screens or shades 19 are employed. The 65 manner in which these mirrors intercept the light rays or beams for forming the aforementioned letter is readily obvious from the construction shown in Figure 5 and therefore a detailed description thereof is thought 70 unnecessary.

It will thus be seen from the foregoing description, that I have provided a highly novel advertising device for displaying words, letters, figures, or other characters 75 in the air at night so that the same will be visible from a suitable distance and will further attract considerable attention. The simplicity in which the present advertising device is constructed enables the reflecting 80 mirrors to be arranged in any desired manner for displaying any predetermined figure or character, and furthermore an advertising medium of this nature will be very inexpensive.

85 While I have shown the preferred embodiment of my invention it is to be understood that minor changes in the size, shape and arrangement may be made without departing from the spirit and scope of the appended 90 claims.

Having thus described the invention, what I claim as new and desire to secure by Letters Patent is:—

1. In an apparatus of the character described, a source of light, reflectors arranged in predetermined spaced relation with respect to said source of light and with respect to each other for intercepting and transmitting the light rays projected from 100 said source in different directions, whereby predetermined characters are formed in the air.

2. In an apparatus of the character described, a source of light, reflectors arranged in predetermined spaced relation with respect to said source of light and with respect to each other for intercepting and transmitting the light rays projected from 110 said source in different directions, whereby predetermined characters are formed in the air, and means at the ends of the characters for preventing the further projection of said light rays.

3. In an apparatus of the character described, a source of light, reflectors arranged in predetermined spaced relation with respect to said source of light and with respect to each other for intercepting and transmitting the light rays projected from 120 said source in different directions, whereby predetermined characters are formed in the air, means at the ends of the characters for preventing the further projection of said light rays, said last mentioned means comprising 125 a plurality of shades.

4. In a process of the character described, consisting in transmitting light beams in the

air from different positions and in different directions, and arranging the light transmitting means so that the beams transmitted form the outline of a character.

5. In a process of the character described, consisting in transmitting light beams in the air from different positions and in different

directions, and then intercepting the same, and arranging the intercepting means in such positions that the beams deflected therefrom will form the outline of a character. ¹⁰

In testimony whereof I affix my signature.

WLADIMIR W. MITKEWICH.
